UNITED STATES PATENT OFFICE.

JOSEPH HARRY GRUVER, OF BALTIMORE, MARYLAND, ASSIGNOR OF ONE-HALF TO
FRANCIS NORRIS, JR., OF RASPEBURG, MARYLAND.

NON-REFILLABLE BOTTLE.

1,042,669.

Specification of Letters Patent.

Patented Oct. 29, 1912.

Application filed November 4, 1911. Serial No. 658,563.

To all whom it may concern:

Be it known that I, JOSEPH HARRY GRUVER, a citizen of the United States, residing at Baltimore, Maryland, have invented 5 certain new and useful Improvements in Non-Refillable Bottles, of which the following is a specification.

My invention relates to non-refillable bottles, and my object is to provide a stopper of 10 economical construction and of high efficiency in operation, and the invention consists in the features and combination and arrangement of parts hereinafter described and particularly set forth in the appended 15 claims.

In the accompanying drawings Figure 1 is 20 a view of a bottle neck in section with my invention applied thereto; Fig. 2 is a view similar to Fig. 1 with the bottle inverted; Fig. 3 shows the position of the parts when the bottle has been turned from inverted position to a horizontal position; Fig. 4 is a 25 detail view of the sliding valve member, this view being a bottom sectional plan view; Fig. 5 is a sectional view of a modified form of seat for the ball valve. Figs. 6 and 7 are 30 views, similar to 1 and 2, of the preferred form.

In these drawings, 1 indicates a bottle 35 neck of standard form having within it a bead or slight enlargement at 2. The improved stopper comprises a sleeve 3 having flanges 4, 5, at the top and bottom, the upper flange being of a diameter to fit closely 40 within the bottle neck, and to rest upon the bead 2, the lower flange 5 being of smaller diameter so as to pass the said bead when the device is thrust into the bottle neck. Packing is interposed at 6 between the sleeve 45 and the wall of the bottle neck, being held by the upper and lower flanges, this packing being, for instance, of cork, rubber, or other material. Within this sleeve is mounted to 50 slide a valve member 7, this being of cylindrical form and having a top plate 8 to rest upon the upper end of the sleeve 3, so that when in this position, as shown in Fig. 1, the bottle will be closed at this point against the entrance of liquid, and, if desired, suitable packing may be applied at the point 55 where the rim of the cover 8 seats itself upon the rim of the sleeve 3. This valve member 8, in addition to furnishing a closure at the upper part of the device as just described, also has means for further closing

the device against the entrance of liquid, as will be hereinafter described. The valve member 7 is provided with openings 9 for the passage of the liquid, these openings being near the top thereof and directly under 60 the cover portion at 8. The lower end of the member 7 carries a valve seat 10 for a ball valve 11, this valve seat member 10 being screw threaded upon the lower end of the sliding valve member 7. 65

When the parts are in the position shown in Fig. 1, the cover or top 8 of the valve member 7 furnishes a closure at the upper part of the device, and the ball valve seats itself upon the seat 10, and furnishes a closure at the lower end of the device, thus affording double security against the inlet of fluid. Within the sliding valve member 7 a prong-carrying member 12 is held by bearing upon the flaring walls at 13 of the sliding valve member 7, the screw cap or seat 10, when in place, serving to hold this pronged member in proper relation to the sliding valve member 7. This pronged member extends only part way of the length of the 75 sliding valve member 7, and its prongs 14 are turned slightly inwardly at the points 15. 70

When the bottle is inverted, as shown in Fig. 2, the sliding valve member 7 moves through the sleeve 3 to the position 80 shown in Fig. 2, and this permits the liquid to flow through the opening in the valve seat 10, thence through the prong member, and out through the openings 16 between the prongs, it being understood that the ball 85 member 11 is now held by the ends of the prongs, and thence the liquid passes through the openings at 9 and past the cover 8 to be discharged from the bottle. It will be noted that this cover 8 is of elliptical form, presenting comparatively wide spaces along its minor diameter, as shown in Fig. 1, whereas along its major diameter the cover fits closely 90 against the inner walls of the bottle neck. In other words, these extended portions of the cover overlie the openings at 9. The purpose of this is to prevent the introduction of a wire between the edge of the cover 8 and the bottle neck at those points on the circumference of said cover which overlie 95 the openings 9. These extended portions of the cover form guards in line with the openings 9 to prevent the insertion of a wire to tamper with the ball valve or other parts of the device. Now, when the bottle is turned 100 105 110

from the position shown in Fig. 2 to the horizontal position shown in Fig. 3 or substantially this position, the ball valve will roll to and close upon the seat 10 to prevent the inlet of fluid, any slight pressure of the fluid causing the ball to roll and seat itself. This action will take place before the sliding valve member 7 begins to slide back from its position shown in Fig. 3 to that shown in Fig. 1.

Various changes may be made in the specific form of the device or members thereof; for instance, instead of having the valve seat at 10 for the ball provided with an upwardly extending lip at 17, this valve seat may be formed as shown in Fig. 5.

In Figs. 6 and 7 I show a form of stopper in which I accomplish the same result as is accomplished by the form shown in Figs. 1 and 2, but with a simpler construction and with less parts. Instead of using the pronged member 12 as a means for guiding and controlling the ball valve, I form the sliding valve member 7' so as to perform all the functions of the sliding valve member shown in Fig. 1, and also the functions of the pronged member 12. For this purpose the sliding valve member is provided with ribs 12' on its interior, these being formed in any suitable manner but preferably by swaging the metal of the sliding valve member inwardly as shown at various points, thus forming the ribs, and these ribs at their inner ends terminate in stops or shoulders 15' so that the movement of the ball toward the cover or closed end of the sliding valve member will be limited as shown in Fig. 7, which shows the bottle inverted for pouring the liquid. When in this position the ball leaves its seat 10' and rolls toward the other end of the sliding valve member, being arrested and held at a point above the lateral openings 9' by contact with the stops 15'. When the ball is held in the position shown in Fig. 7 the liquid will be free to pass this ball through the spaces between the ribs 12' and thence out through the openings 9' to be discharged from the bottle. The cover 8' of the sliding valve member is longer on one diameter than the other, as in the form first described. The valve seat 10' consists of a ring held by the shell of the sliding valve member as shown

in Fig. 6, the said shell being bent at 10° over the ring which is thus held against the shoulder 10' on the shell. The sliding valve member is formed all in one piece and at one operation.

Certain of the subject matter herein disclosed has been made the subject of another application filed by me, May 20, 1912, #698,555, this subject matter consisting of a fixed seat member, a sliding valve member moving therein and having a cover portion with lateral openings below the same and a central opening, a ball valve to engage the central opening and a pronged member held in a sliding valve member, the prongs of which have stops to limit the movement of the ball to a point removed from the lateral openings.

I claim as my invention:

1. In combination with a sleeve to be fixed within the hollow neck, a sliding valve member having a closed top with a portion thereof to rest on the sleeve to form a closure, and with a lateral opening in the wall below the said closed top, said closed top being of substantially elliptical form, with its major axis in line with the lateral openings to provide a portion to guard said lateral openings, and a ball valve within the sliding valve member to close an opening at the lower end thereof, substantially as described.

2. In combination in a non-refillable bottle stopper, a sleeve to fit within the bottle neck, a hollow sliding valve member of cylindrical form fitted to slide through the sleeve having a closed top with lateral openings below said closed top, and with a lower valve seat, a ball within the hollow cylindrical sliding valve member and carried thereby, guides for the ball carried on the inside of the sliding valve member with spaces between the said guides, said guides terminating in stops, substantially in the plane of the lower edges of the lateral openings, substantially as described.

In testimony whereof I affix my signature in presence of two witnesses.

J. HARRY GRUVER.
